WITNESS:

INVENTOR.

BY *E.E. Pearey*

Victor J. Evans

ATTORNEY.

UNITED STATES PATENT OFFICE.

ERNEST E. PEAVEY, OF BANGOR, MAINE.

TOY.

1,330,000.

Specification of Letters Patent.

Patented Feb. 3, 1920.

Application filed June 24, 1919. Serial No. 306,306.

To all whom it may concern:

Be it known that I, ERNEST E. PEAVEY, a citizen of the United States, residing at Bangor, in the county of Penobscot and State of Maine, have invented new and useful Improvements in Toys, of which the following is a specification.

This invention relates to a novel construction of toy and the invention comprises a cannon with means for projecting a ball therefrom and a movable target which when struck by the ball will drop behind a stationary part and thus be hidden from view.

The invention also comprises means for permitting the cannon to disappear behind a fort after being fired.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a side view of the invention.

Fig. 2 is a plan view.

Figs. 3, 4 and 5 are detail views.

In these views, 1 indicates a platform on which the different parts of the toy are arranged. Adjacent one end of the platform is located a pair of standards 2 which are suitably secured to the platform. The standards are provided with holes adjacent their upper ends to receive the shaft 3. The shaft has both rotary and sliding movement in said holes and a sleeve 4 on the shaft and between the standards acts to limit the longitudinal movement of said shaft. The outer end of the shaft is provided with a handle 5 which has a square part 6 thereon adapted to engage with a square recess 7 formed in the outermost standard around the opening therein. Thus when the shaft is moved inwardly so that the square part 6 will engage said square recess said shaft is held against rotary movement. On its inner end the shaft carries a member 8 which is secured to the shaft adjacent one end thereof so that said member tends to rotate the shaft so that it may assume its lowermost position, shown

in dotted lines in Fig. 1. I prefer to make this member of a form to represent a ship. To hide this member from view when the same is in its lowest position I place upright strips 9 before the same, said strips being secured to the platform. I may paint these strips so that they will represent water. About midway the ends of the platform is located a partition 10 painted to represent a fort. The upper edge is provided with a recess 11 through which projects the muzzle of a cannon 12. This cannon is mounted on the standards 13, in rear of the fort and I form these standards in two parts and hinge the two parts together, as at 14. In this way the cannon can be moved downwardly and rearwardly so as to disappear behind the fort. When in lowered position the end of the cannon will rest on a support 15 secured to the platform and having its upper edge recessed to receive the cannon. If desired a second pair of standards similar to the pair 13 may be placed immediately behind the fort and secured to the cannon. This second pair is shown in dotted lines at 16. The cannon is provided with a spring plunger 17 for propelling a ball such as 18 from the muzzle of the cannon. The plunger is held in retractive position by means of a slot 19 formed in the plunger and adapted to engage with a projection 20 formed at the rear end of the cannon.

It will thus be seen that when the plunger is released it will project the ball from the cannon and said ball will strike the target 8 and thus move said target with the shaft 3 rearwardly so as to release the square part 6 from the square recess 7. This will permit the target to drop by gravity behind the strips 9 so as to give the effect of a sinking ship. By quickly releasing the cannon after the firing the same will drop behind the fort and thus act like a disappearing gun.

Having thus described my invention, what I claim is:—

1. A toy of the class described comprising a platform, an upright partition on the platform representing a fort, a cannon hingedly connected with the platform behind the partition, partitions in front of the fort for representing the sea, a rotatable target representing a ship and means for causing the

target to rotate behind the partitions representing the sea when struck by a ball projected by the cannon.

2. A toy of the class described comprising a platform, a pair of standards thereon, a shaft journaled in said standards and having sliding movement therein, said shaft having a square part thereon and one of

the standards having a square recess for receiving said square part, a member, representing a ship, secured to the shaft adjacent its lower end and a cannon on the platform for projecting a ball against the member. 10

In testimony whereof I affix my signature.

ERNEST E. PEAVEY.
